UNITED STATES PATENT OFFICE.

LEWIS O. HOWELL, OF PHILADELPHIA, PENNSYLVANIA, ASSIGNOR TO FLORENCE S. HOWELL, OF PHILADELPHIA, PENNSYLVANIA.

DESIGN FOR A COMBINED FORCE-CUP AND CLEANER.

46,996.

Specification for Design.

Patented Feb. 23, 1915.

Application filed November 12, 1914. Serial No. 871,808. Term of patent 14 years.

To all whom it may concern:

Be it known that I, LEWIS O. HOWELL, a citizen of the United States, residing at Philadelphia, in the county of Philadelphia and State of Pennsylvania, have invented a new, original, and ornamental Design for Combined Force-Cups and Cleaners, of which the following is a specification, reference being had to the accompanying drawing, forming a part thereof.

I claim:

The ornamental design for a combined force cup and cleaner, as shown.

LEWIS O. HOWELL.
